UNITED STATES PATENT OFFICE.

CLARENCE E. MORRISON, OF ALBANY, NEW YORK.

DUPLICATOR.

Application filed January 15, 1926. Serial No. 81,520.

This invention relates to duplicating machines. The object of this invention is to provide a simple, efficient, and comparatively inexpensive rotary duplicating machine; one which will be more simple and compact than present devices of the same general character; and a cylindrical stencil-holder for use thereon, which will have a greater effective working area than do the present types of such cylinders having the same length and diameter, and one wherein the surface to be inked may be wholly exposed, thereby permitting the proper inking thereof to be easily accomplished, and without removing, or loosening the fastenings of the stencil.

The manner in which I accomplish my object is illustrated in the accompanying drawings, in which:

Fig. 1 is a top plan view of my improved, simplified, rotary duplicator; Fig. 2 is a rear elevation, and Fig. 3 is a side elevation of the same. Fig. 4 is a cross-section through the stencil-holder and illustrates the manner in which the ends of the stencil sheet are secured to the stencil-holder, and the manner in which the cylinder may be opened and the inner surface thereof exposed.

The same reference characters refer to the same parts throughout the several views.

Referring to the drawings, the frame of my improved rotary duplicator preferably consists of a single piece, which may be formed from a sheet of metal, and which comprises a base plate, b^2 , at each end whereof is an upstanding end piece, b^3 and b^4 , each of which carries an extension, b^5 or b^6 , on the outer side and along the top edge of which is formed a rib b^7 or b^8 . Extending downward from, and then parallel to the base plate b^2 , so as to form a C-shaped recess adapted to admit the edge of a table or other convenient support, is a post b^9 , in the horizontal portion of which is a thumb-screw b^{10} , whereby the device may be secured to such support.

In the upper ends of the parts b^3 and b^4 , are formed suitable notches or open bearings, 22, adapted to act as journals for the trunnions, 20, on the cylindrical stencil-holder SH, and in the lower portions thereof are formed inverted U-shaped slots, s^3 , in line with each other, and in one end or the other of which the shaft, p , of the press roll is journaled, in the inner ends when in working position and in the outer ends when out of service.

Slidable on the extensions b^5 and b^6 , and bridging the space therebetween, is a feeding table T, preferably formed of sheet metal, each end of the table being bent downwardly, then inwardly, to form a groove adapted to fit slidably on the ribs, b^7 or b^8 , on the projections b^5 or b^6 . The outer or forward edge of the table is turned up to form a stop, t .

The press roll, P, of my improved device is provided with a shaft, p , the ends of which are journalled in the inner end of the slots s^3 , when the parts are in operative positions. The slots s^3 are so positioned that when the shaft, p , is journalled in the inner ends thereof the press roll will prevent the trunnions, 20, on the stencil-holder SH, from seating in the bottom of the notches 22, thereby permitting the springs, S, to force the stencil against the press roll. The other or outer ends of the slots s^3 , are so positioned that when the press roll is forced over until the shaft, p , is journalled therein, the press roll is removed a sufficient distance from the stencil-holder to insure its being out of contact therewith when the trunnions 20 are forced downward to a seat in the bottom of the notches, 22, under the urge of the springs S.

My improved cylindrical stencil-holder SH, comprises two complementary half cylinders 23 and 24, (each of which is perforated in the usual manner so that ink spread on the inner surface thereof will be absorbed by the ink pad), so hinged together, as at h , that the cylinder may be opened out as shown in Fig. 4, and indicated by dotted lines in Fig. 3. The free edge of the half-cylinders are preferably fastened together by suitable spring latches 25. In one of the half-cylinders, 23, each end piece, or half head carries a trunnion, 20, adapted to support the cylinder, and on one of these trunnions is secured a crank 26 and handle H, whereby the cylinder may be rotated at will; the end pieces in the other half, 24, of the cylinder are notched to fit over the trunnions.

Near the free edge of one half-cylinder, there is provided a number of hook-like projections 27, adapted to enter holes in the bound end of the stencil so as to secure the same thereto. For fastening the other end of the stencil I use a channel-like spring clip 28. The free edges of the half-cylinders may be depressed so that the hooks 27, latches 25, and the clip 28, will all lie below,

or inside the curved plane of the cylinder.

The cylindrical stencil-holder is held in place, and forced against the press roll (when it is in operative position) by the springs S, one end of these springs being secured preferably permanently, to the trunnions, the other ends hooked under the projections b^5 or b^6 on the frame of the device. The springs, S, have dual functions, that of providing tension between the press roll and the stencil-holder, and of securing the stencil-holder in place in the device.

It is self evident that the device shown may be used with but a half cylinder when but a short stencil is required; i. e., the part 24 of the cylinder shown may be omitted and the free end of the stencil clipped to the edge of the part 23 opposite the side whereon the hooks 27 are located.

20 A rotary duplicator, or an oscillating duplicator if but a half cylinder is used, constructed substantially as illustrated and described, will be simple, efficient, and comparatively inexpensive; while the increased 25 available working surface of the hinged two-part stencil-holding cylinder, due to the absence of the usual gap through which the device is to be inked, and which is necessary with the usual small diameter cylinders, 30 makes it possible to obtain the desired length of working surface on a smaller diameter cylinder and so makes for compactness; and the ability to open out the two parts of the 35 stencil-holder, and so expose the whole of their inner surfaces, makes it a very easy matter to ink or re-ink the ink pad without removing and re-applying the stencil.

Providing for the shifting of the position of the press roll for the operative to the inoperative position, in the manner shown and described, permits the press roll to be removed at will, without withdrawing the shaft therefrom; and this arrangement also makes easily possible the application of a covering sheet to the stencil so that the same will be maintained in usable condition for a considerable period of time, and not become damaged by being under tension or pressure at the point where it may have stopped when 50 in contact with the cylinder.

I claim:

1. In a duplicator, a frame on the under side whereof is formed a clamping means whereby the device may be detachably secured to a support, and which carries on the upper side thereof a spaced pair of upright brackets each of which has an open bearing formed in the top thereof, and near the bottom whereof is an inverted U-shaped slot adapted to pass the ends of a shaft carrying a press roll, and each end thereof to form a bearing therefor; a press roll, journalled in said slots; a rotatable stencil-holder, with pivot pins at the ends thereof, journalled 65 in the open bearings in the tops of said

brackets; and springs holding said stencil-holder in its bearings, and normally forcing the working surface thereof into intimate contact with the working surface of said press roll.

2. In a duplicator, a frame on the under side whereof is formed a clamping means whereby the device may be detachably secured to a support, and which carries on the upper side thereof a spaced pair of upright brackets each having a forwardly projecting arm, each of said brackets having an open bearing in the top thereof, and near the bottom thereof an inverted U-shaped slot adapted to pass the ends of the shaft of a press roll, and each end thereof to form a bearing therefor; a table plate bridging the space between the forwardly projecting arms of said brackets; a press roll, journalled in said slots; a rotatable stencil-holder, with pins at the ends thereof, journalled in the open bearings in the tops of said brackets; and springs holding said stencil-holder in its bearings, and normally forcing the working surface thereof into intimate contact with the surface of said press roll.

3. In a duplicator, a frame on the under side whereof is formed a clamping means whereby the device may be detachably secured to a support, and which carries on the upper side thereof a spaced pair of upright brackets each having a forwardly projecting arm, each of said brackets having an open bearing in the top thereof, and near the bottom thereof an inverted U-shaped slot adapted to pass the ends of the shafts of a press roll, and each end thereof to form a bearing therefor, said slots so positioned that when the press roll is journalled in one end thereof it will be in contact with the stencil-holder, and when in the other end thereof it will be out of contact with said holder; a table slideable on, and bridging the space between, the forwardly projecting arms of said brackets; a resiliently surfaced press roll, journalled in said slot; a rotatable cylindrical stencil-holder, comprising two complementary parts hinged together longitudinally, one of said parts having trunnions formed on the ends thereof, journalled in said open bearings in said brackets; and springs holding said stencil-holder in its bearings, and normally forcing the working surface thereof into intimate contact with the working surface of said press roll.

4. A frame for a duplicating machine, and comprising a base plate portion; a clamping portion beneath said base portion; and a bracket projecting upward from each end of said base portion, the upper ends of said bracket having an open bearing formed therein and adapted to act as journals for a rotatable stencil-holder, and each having an inverted U-shaped slot near the base thereof, said slot so shaped, and so positioned with

reference to said open bearings, that a press roll may be journalled in either end thereof, passed from one end to the other without being removed therefrom, and when journalled in the inner ends of said slots will normally be in operative contact with a stencil-holder in place in said open bearings, and when moved to the outer ends of said slots will be out of contact with said stencil-holder.

5 5. In a frame for a duplicating machine, an aligned pair of inverted U-shaped bearing slots adapted to have a press roll journalled therein, said slots so shaped, and positioned with reference to the point at which a 10 rotatable stencil-holder is journalled in the frame, that a press roll in place in one end thereof would normally be in operative contact with said stencil-holder, and when moved to the opposite ends of said slots will 15 be out of contact therewith.

6. A cylindrical stencil-holder for a duplicating device, and comprising: a complementary pair of hollowed, perforated, half-cylinders hinged together longitudinally, the 20 ends of one of said pair provided with pivot pins, the free edges of said half-cylinders provided with means whereby the ends of a

stencil sheet may be secured thereto, and with means whereby the two may be separably secured together.

7. A cylindrical stencil-holder for a duplicating device, and comprising: a complementary pair of hollowed, perforated, half-cylinders hinged together longitudinally, the ends of one of said pair provided with 30 projecting pivot points, the free edge of one of said half cylinders provided with hook-like projections whereby one end of a stencil sheet may be secured thereto; and means whereby the free edges of said half cylinders 35 may be separably secured together.

8. A stencil-holder for a rotary duplicating machine, comprising: a complementary pair of hollowed, perforated, half cylinders hinged together longitudinally, the axis of 40 the hinge substantially in the plane of the periphery of the cylinder.

9. A duplicating machine substantially as illustrated and described, and including a 45 hollow perforated cylindrical stencil-holder, 50 divided, and hinged together longitudinally.

In testimony whereof I have affixed my signature.

CLARENCE E. MORRISON.
